10 adjacent each end of the windshield 12 thereof is a socket 54 which opens upwardly and receives the leg 46 of an adjacent arm 34. Each socket is provided adjacent its lower end with a notch or recess 56 for the reception of the retaining ball 52 of the leg 46 of the arm 34 which enters the socket 54, and formed on the socket adjacent its lower end is an outwardly extending ear 58 to which is pivoted one end of a prop 60. This prop is provided near its opposite end with an elongated, longitudinally extending slot 62, the inner end of which terminates in an enlarged opening 64 through which the head of a pin 66 carried by a bracket 68 on an adjacent edge of the panel 20 may be entered into the slot 62. The shank of the pin 66 rides in the slot 62 so that the panel may be moved to raised or lowered positions, as will be readily understood upon reference to the drawings. In order to hold the panel 20 in its elevated position, the end of the slot 62 adjacent the free end of the arm or prop 60 is equipped with a notch 70 into which the shank of the pin 66 may engage when the panel is in its uppermost position.

In use, it will be understood that the panels 20 are mounted on the front end of the vehicle as suggested in Figure 1 with the legs 46 of the arms 34 mounted in their respective sockets 54. Obviously, the panels may be easily and quickly disconnected from their position on the windshield simply by swinging them downwardly until the heads of the pins 66 align with the openings 64 so that the props may be disconnected, after which the legs 46 of the arms 34 may be extracted from their positions within the sockets 54. When in position, the operation of the panels is obvious from the drawings, and they may be held in elevated position by engagement of the shanks of the pins 66 in the recesses 70.

While in the foregoing there has been shown and described the preferred embodiment of this invention, it is to be understood that minor changes in the details of construction, combination and arrangement of parts may be resorted to without departing from the spirit and scope of the invention as claimed.

Having described the invention, what is claimed as new is:

1. In combination with a demountable frost shield and sun visor for the windshield of a motor vehicle which includes a pair of panels each being of a size and shape to cover one-half of the windshield of a motor vehicle, means for attaching the shield to the vehicle including an L-shaped arm pivotally connected to each panel adjacent one end thereof, a socket fixed to the body of a vehicle adjacent each end of the wind-

shield thereof, each socket receiving one leg of each L-shaped arm and a prop pivoted to each socket and pivotally and slidably connected to an adjacent end of an adjacent panel for holding said panel elevated and out of windshield covering position, and means carried by the leg of each arm opposite that connected to its respective panel frictionally to engage the wall of its respective socket removably to hold an arm in its respective socket.

2. In combination with a demountable frost shield and sun visor for the windshield of a motor vehicle which includes a pair of panels each being of a size and shape to cover one-half of the windshield of a motor vehicle, means for attaching the shield to the vehicle including a sleeve fixed to each panel adjacent one end thereof, said sleeve having aligned transverse openings therein, a pair of L-shaped arms, one leg of each arm entering a sleeve and having an annular groove therein which registers with the transverse openings in its respective sleeve, a pin entering each opening and projecting part way into the groove in its respective sleeve, a spring clip encircling each sleeve intermediate its ends and holding the pins against accidental withdrawal and a socket fixed to the body of the vehicle adjacent each end of the windshield to receive the leg of an adjacent arm opposite that which enters the sleeve.

3. In combination with a demountable frost shield and sun visor for the windshield of a motor vehicle, said frost shield including a pair of panels, each panel being of a size and shape to cover one-half the windshield, means for attaching the frost shield to the vehicle including an L-shaped arm pivotally connected to each section adjacent one end thereof, a socket fixed to the body of the vehicle adjacent one end of the windshield thereof, each socket receiving one leg of each L-shaped arm and a prop pivoted to each socket and pivotally and slidably connected to an adjacent end of an adjacent section for holding said section elevated and out of windshield covering position.
